Primary Examiner — T Chase Nelson(74) *Attorney, Agent, or Firm* — Wolf, Greenfield & Sacks, P.C.(57) **CLAIM**

The ornamental design for an outsole, as shown and described.

DESCRIPTION

FIG. 1 is a bottom, front, and right side perspective view of an outsole according to our new design;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof; and,
 FIG. 7 is a bottom plan view thereof.

The broken lines shown in FIGS. 1-5 show portions of the outsole that form no part of the claimed design. The broken lines and unshaded inner surfaces in the FIG. 6 view show portions of the outsole that form no part of the claimed design.

1 Claim, 7 Drawing Sheets(56)
